[57] **CLAIM**

The ornamental design for a container for a liquid or a gel, substantially as shown and described.

DESCRIPTION

FIG. 1 is an elevational view of a container for a liquid or a gel showing my new design, the opposite side being a mirror image thereof;

FIG. 2 is an elevational view looking from the right of FIG. 1;

FIG. 3 is an elevational view looking from the left of FIG. 1;

FIG. 4 is a top plan view; and

FIG. 5 is a bottom plan view thereof;

FIG. 6 is an elevational view showing an alternate embodiment of my new design, the opposite side being a mirror image thereof;

FIG. 7 is an elevational view looking from the right of FIG. 1;

FIG. 8 is an elevational view looking from the left of FIG. 1;

FIG. 9 is a top plan view; and

FIG. 10 is a bottom plan view thereof.

FIG. 2

FIG. 1

FIG. 3
